(57) **CLAIM**

The ornamental design for a sample changer, as shown and described.

DESCRIPTION

FIG. 1 is front perspective view of a sample changer;
FIG. 2 is a left side elevation view of the FIG. 1 device;
FIG. 3 is a front elevation view of the FIG. 1 device;
FIG. 4 is a right side elevation view of the FIG. 1 device;
FIG. 5 is a rear elevation view of the FIG. 1 device;
FIG. 6 is a top plan view of the FIG. 1 device; and,
FIG. 7 is a bottom plan view of the FIG. 1 device.
The broken lines illustrate unclaimed portions of the sample
changer and form no part of the claimed design.
